The ornamental design for a diffuser, as shown and described.

DESCRIPTION

FIG. 1 is a top isometric view of a top portion of a diffuser;
FIG. 2 is an elevational view of a first side of the top portion
of the diffuser of FIG. 1;

FIG. 3 is an elevational view of a second side of the top
portion of the diffuser of FIG. 1, wherein the second side is
opposite the first side;

FIG. 4 is an elevational view of a third side of the top portion
of the diffuser of FIG. 1;

FIG. 5 is an elevational view of a fourth side of the top portion
of the diffuser of FIG. 1, wherein the fourth side is opposite
the third side; and,

FIG. 6 is a top plan view of the top portion of the diffuser of
FIG. 1.

The subject matter shown in the broken lines in the figures in
dashed lines is for illustrative purposes only and forms no part
of the claimed design.
